WIRE STRAIGHTENING MACHINE

Jacob T. Leech, Beaver, Pa.

Application June 18, 1930, Serial No. 461,948

23 Claims. (Cl. 153—37)

This invention relates to the art of straightening wire and especially wire of relatively large diameter which is to be subsequently cut up into straight lengths to be sold as rods.

5 It is well recognized in the art that wire which is drawn through a die and wound up upon a reel, the tension of drawing being effected by the winding up of the wire on the reel, has to be straightened before it can be cut up into straight 10 lengths suitable, for instance, as stock for screw machines. This is due to the fact that as the wire winds upon the reel there is a difference in diameter between the inner surface and the outer surface of the coil equal to the diameter of the 15 rod or wire. This necessitates the relative stretching of one side of the wire and the relative compression of the other side.

The most successful mechanism for straightening wire heretofore provided comprised a revolving head adapted to be rotated at high speed. 20 The wire is passed through this head, which is substantially in the shape of a cylinder, and within the head are a series of shoes which bear against the wire, one of these shoes having the 25 wire engaging face thereof eccentric so as to bow the wire as it passes through the head. The shoe, being carried by the head, rotates around the wire so that with a revolution of the head the wire has been bowed in every direction from the normal center line.

This type of apparatus is most generally known as the Schuster type of straightener. The wire must be drawn longitudinally through the head so that it will be progressively bowed by the eccentric shoe. These shoes exert a considerable friction to resist the endwise movement of the wire. All of the shoes bear against the wire as the head rotates, and this is a further source of friction. The speed at which the wire can be 30 straightened depends upon the speed at which the head can be rotated. If the head is rotated too fast and the speed of the wire is increased, the heat of friction galls or mars the wire so that it cannot be used as first class stock. Therefore, 35 of necessity, the wire can only be straightened at a moderately low rate of speed. It is estimated that there should be approximately three revolutions of the straightener for each inch of travel of the wire, and the present maximum 40 speed is 1500 revolutions per minute. Consequently the wire cannot be straightened much faster than forty feet per minute.

According to the present invention there is 45 provided a machine in which the straightening elements do not have to revolve about the wire,

thus eliminating one source of friction and in which the wire engages rollers whose axes are transverse to the direction of travel of the wire, so that there is practically no friction by reason of the longitudinal travel of the wire through 5 the straightening mechanism.

The invention may be readily understood by reference to the accompanying drawings in which

Figure 1 is a more or less diagrammatic view 10 of a complete straightening unit embodying my invention;

Figure 2 is a longitudinal section through the straightening head itself;

Figure 3 is an end elevation of the straightening head;

Figure 4 is a transverse section through the straightening head in substantially the plane of line IV—IV of Fig. 2;

Figure 5 is a transverse section through one 15 of the guide roll units;

Figure 6 is a longitudinal section in substantially the plane of line VI—VI of Fig. 5; and

Figures 7, 8, 9, and 10 are fragmentary views 20 showing a view of the many different roll arrangements which may be provided in the straightening head and in the guide roll units 25 and showing how different arrangements of rolls can be used for wire of non-circular cross-section.

Referring to the drawings, 2 designates the bed 30 of a machine of suitable construction. Carried on the bed is a straightening head or flexing unit 3. At each end of the straightening head unit 3 are one or more guide roll units 4. I have shown two of these guide roll units at each end of the straightening head unit. At the entrance end of the machine I have indicated pinch rolls 5 and at the finishing end of the machine I have shown similar rolls 6.

The straightening head unit shown comprises 40 a rotatable head 7 having grooves 8 in the periphery thereof, these grooves being for the accommodation of driving belts, the driving belts and driving motor not being shown. On each end face of the rotatable member 7 is a trunnion 45 plate 9 having a hollow trunnion portion 10. These trunnion portions 10 are supported on ball-bearings 11, the ball-bearings being carried in recesses in stationary supporting frames 12. By reason of this arrangement the head 7 can be 50 rotated at high speed and comparatively little friction in the stationary stands 12.

Carried in the revolving head 7 is an adjustable frame 13, best shown in Fig. 4. This frame, received within a window 14 in the member 7, can 55

be positioned by the operation of adjusting screws 15, the ends of which are accessible on the periphery of the member 7, as clearly shown in Fig. 4.

Carried in the frame 13 is a cylindrical depressing unit 16. Ball-bearings 17 are preferably interposed between the periphery of the cylindrical member 16 and the circular opening 18 in the frame 13. These ball-bearings 17 permit the unit 16 to remain stationary while the head 7 with its adjustable frame 13 revolves around it. In the depressing head or cylinder 16 are a plurality of longitudinally extending intersecting slots 19. In each slot I have shown a wire engaging roller 20 carried on a pin 21. The slots 19 intersect at a central opening 22 in the member 16, and the peripheries of the rollers 20 project into the central opening 22. In Figs. 1, 2, 3, and 4 I have shown four of these rollers 20. The peripheries of them are concave so that together they define a circular pass 23 conforming to the diameter of the wire to be straightened and through which the wire to be straightened is passed. In Figs. 1, 2, and 3 I have shown this pass 23 as being directly at the center of the unit. However, in actual operation this pass is shifted to an eccentric position with reference to the center of rotation of the head 7. This adjustment may be effected by movement of the frame 13 through the operation of the adjusting screws 15. This may be readily understood by reference to Fig. 4 wherein the line A—A represents the vertical center line of the member 7 and the line B—B represents a vertical center line through the pass 23 defined by the several rollers 20.

The guide roll units 4 arranged at each side of the main flexing or depressing unit 3 comprise a standard 25 having a hollow head 26 within which is a removable cylinder 27. The cylinder 27 carries a plurality of small guide rollers 28 arranged in groups and forming a central pass 29 conforming to the shape and size of the wire being straightened. The cylinders 27 are adjustably retained in place by means of clamping screws 30. By loosening the screws 30 it is possible to replace the units 27 when a wire of different size or different shape is to be passed through the machine.

Those guide units immediately adjacent the unit 3 are preferably adjustable longitudinally of the bed 2 so that they may be moved closer to or further away from the unit 3 as conditions may require. The passes 29 formed by the several sets of guide rollers 28 are all in alinement, and the axis of this pass coincides with the axis of rotation of the head 7 in the unit 3. The pass 23 formed by the rollers 20 is eccentric to the axis of the passes 29 through the several groups of rollers 28.

In the operation of the machine, the wire is fed through the rollers 5, through the passes 29 of the guide roller units 4, then through the pass 23 formed by the rolls 20 in the flexing unit. From there it passes through the other guide units 4 and the pinch rolls 6. Since the pass 23 is eccentric to the axis of the wire, the wire is bowed in passing from the guide unit 4 on one side of the unit 3 to the guide unit 4 on the other side of the unit 3. This is shown in Fig. 1.

By moving the two units 4 immediately adjacent the unit 3 closer to the unit 3, the curvature of the wire is made more abrupt and by spreading the units 4 further apart, the curvature is made more gradual. It is for this reason that the units 4 are preferably adjustable longitudinally 75 of the bed 2.

After the wire has been started through the machine as described, the head 7 is rotated at high speed by means of belts (not shown) engaging in the grooves 8. The frame 13 in the head 7 of course revolves with the head, but it is, during the operation of the machine, eccentrically positioned in the head. The frame 13 carries the member 16 in which are the rolls 20. Due to the presence of the ball-bearings 17 the frame 13 rotates about the member 16. By this arrangement the member 16, in which are the depressing rollers 20, while not rotating, will wobble or gyrate through a complete circle with each revolution of the head 7. For instance, viewing Fig. 4, when the head 7 has rotated 180 degrees from the position shown, the line corresponding to the line B—B passing through the center of the pass 23 would coincide with the line C—C. With a rotation of 90 degrees from the position shown in Fig. 4 the line B—B would coincide with the line A—A, but the center of the pass would be raised or lowered from the position shown an amount equal to the eccentricity of the pass with reference to the center of rotation of the head 7. Thus while the member 16 with its rollers 20 does not revolve with the head 7, it is, due to its eccentric mounting of the head, caused to wobble or gyrate. The pass 23, with one revolution of the head 7, describes a complete circle about the center of rotation of the head. I have shown a single group of rollers 20 in the head 16, but under some conditions and with some sizes of wire, more than a single group can be used to advantage.

The center of rotation of the head corresponds with the normal axis of the wire passing through the machine. With each rotation of the head, therefore, it will be seen that the wire is flexed from a normal position in every direction to the same extent by this gyratory or wobbling movement of the member 16 with its rolls 20, the rolls 20 of course engaging the wire. It will be seen also that while the wire is flexed in this way there is no rotational movement of the member 16 about the wire. This means that the peripheries of the rollers 20 are not sliding around on the surface of the wire and the wire is flexed without any considerable friction between the wire and the rollers. The relative movement between the revolving head 7 and the stationary wire occurs in the ball-bearings 17.

In the operation of the machine, the wire is pulled through the machine. The rollers 20, being arranged in the manner shown, provide a rolling surface for the longitudinal travel of the wire with the result that there is little frictional resistance offered to the longitudinal movement of the wire. The flexing unit 3 therefore effectively flexes the wire in every direction from a normal position to the necessary extent, as determined by the adjustment of the screws 15, without there being any relative rubbing action on the surface of the wire at all, either due to the longitudinal movement of the wire or due to the flexing action of the unit, thus constituting a considerable improvement over that type of machine wherein the wire is drawn along the pressure shoes which rotate about the surface of the wire and in contact therewith.

Since there is practically no frictional resistance produced by either the flexing action or the longitudinal movement of the wire, the head 7 can easily be rotated at more than twice the speed of the revolving head of the ordinary type of straightener, and the wire can be accordingly fed through the machine at a very much higher 75

rate. In the absence of any friction between the wire and the straightening unit there is no marring of the finish on the wire, even at the higher speeds. The heat generated in the previous machines has imposed one limitation on the speed at which such machines could be operated. Because the present invention avoids the generation of heat on the surface of the wire, the rubbing action being eliminated, the present invention enables the material to be straightened at a much higher rate of speed and with much more satisfactory results.

In order to positively hold the member 16 against rotation I have shown an arm 31 having an inner end entered in one of the slots 19 and having its other end bent down over the outside of the frame and entered in a keeper 31', the keeper being large enough to allow the arm to oscillate with the movement of the member 16. A spring 31^a causes the arm 31 to follow the movement of the member 16 at all times. The arm functions to hold the member 16 against rotation about its own axis but allows it to move about eccentrically.

In Figs. 1 to 7, inclusive, I have shown four rollers in both the flexing head and the guide units having complementary peripheral portions forming a completely circular pass for use where a circular wire is being straightened. It is not necessary, however, that four rollers be used, as two or more cooperating rolls may be employed. In Fig. 8 I have shown two rollers 32 having concave peripheries. The concavity of the peripheries of these two rollers is such that these two rollers will impart the necessary flexing or wobbling action to the round strip.

In Fig. 9 there are shown complementary rollers 33 and 34, the peripheries of which complement each other to produce a hexagonal pass for accommodating a hexagonal stock. In Fig. 10 I have shown another modification of complementary rollers 35 in which three rollers instead of four are used to produce a hexagonal pass for the accommodation of hexagonal stocks.

It will be obvious to those skilled in the art that other combinations and arrangements of rolls may be used for different cross-sectional shapes of wire being straightened.

While I have specifically described one embodiment of my invention it will be understood that various changes and modifications may be made therein, the same being for the purpose of illustration.

I claim:

1. In a wire straightening machine, a wire flexing unit comprising an inner member having a wire receiving pass therethrough of a shape and diameter conforming substantially to the shape and diameter of the wire to be straightened, an outer member rotatable about the inner one and in which the inner one is eccentrically positioned, a fixed support for the outer member at each end thereof, rotation of the outer member imparting a wobbling motion to the inner one, and means on the fixed support engaging the inner member for holding it against rotation with the outer member.

2. In a wire straightening machine, spaced apart wire guiding units having alined wire receiving and guiding passes therein, a flexing unit interposed between the spaced apart wire guiding units comprising a member having complementary rollers therein whose axes are transverse to the axis of the wire passing through the guides and the peripheries of which define a

wire receiving pass of the shape and size of the wire to be straightened and which is eccentric to the alined passes in the guides, said rollers affording a rolling contact for the longitudinal movement of the wire through said member, and means for moving said member transversely in all directions about the longitudinal axis of the wire as it passes through the guides, said member having a passageway therethrough many times larger than the diameter of the wire and in which the rollers are located whereby the wire contacts only with said guides and the rollers of the flexing unit.

3. In a wire straightening machine, spaced apart wire guiding units having alined wire receiving and guiding passes therein, a flexing unit interposed between the spaced apart wire guiding units comprising a member having complementary rollers therein whose axes are transverse to the axis of the wire passing through the guides and the peripheries of which contact at each side with the peripheries of adjacent rollers to define a wire receiving pass which is eccentric to the alined passes in the guides, said rollers affording a rolling contact for the longitudinal movement of the wire through said member, means for moving said member transversely about the longitudinal axis of the wire as it passes through the guides, and means for holding said member against rotation while adapting itself to the transverse movement of said member.

4. In a wire straightening machine, a rotatable head having hollow trunnions thereon and having a driving surface on its periphery, a frame in which the trunnions are rotatably carried, an eccentrically adjustable frame carried in the head, said second frame having an opening therethrough providing an internal bearing surface, a cylindrical member in said opening about which the second frame may revolve with the head, said member having a wire receiving pass therethrough conforming to the shape and diameter of the wire being straightened, said pass normally being eccentric to the axis of rotation of said head due to the eccentricity of the frame, and means beyond the ends of the trunnions constituting the only wire guiding and supporting elements for holding the wire at each side of the said cylindrical member.

5. In a wire straightening machine, a rotatable head having hollow trunnions thereon, a frame in which the trunnions are rotatably carried, an eccentrically adjustable frame carried in the head, said second frame having an opening therethrough providing an internal bearing surface, a cylindrical member in said opening about which the second frame may revolve with the head, said member having a wire receiving pass therethrough conforming to the shape and diameter of the wire being straightened, said pass normally being eccentric to the axis of rotation of said head due to the eccentricity of the frame, means for adjustably changing the eccentricity of said second frame, and adjustable wire guides beyond the ends of the trunnions constituting the support for the wire at each side of the cylindrical member, the internal diameter of the trunnions being sufficient to provide for the angular displacement of the wire between the cylindrical member and said guides.

6. In a wire straightening machine, a supporting frame structure, a rotatable head carried in said structure, a transversely adjustable frame carried in said head, said second frame having an opening therethrough providing an internal

- bearing surface, a cylindrical member in said opening about which the second frame and head may rotate, said member having a central opening therethrough and having a plurality of rollers 5 therein, the peripheries of which project into the central opening into contact with one another and form a closed wire receiving pass, the axes of the rollers being in a plane at right angles to the axis of rotation of said head, the wire 10 receiving pass formed by said rollers being eccentric to the axis of rotation of the head, and means on the supporting frame structure engaging said cylindrical member to hold it against rotation with the rotatable head.
- 15 7. In a wire straightening machine, a stationary frame structure, a flexing head rotatably supported on said structure, said head having a longitudinal opening therethrough, a transversely adjustable frame in said head having a longitudinally extending opening therethrough, a cylindrical member in the opening in said frame, a bearing being provided between the outside of the cylindrical member and the interior of said frame, means for adjusting said frame transversely of the head, a plurality of rollers carried in said cylindrical member, the peripheries of which cooperate to define a wire receiving pass, the axes of the rollers being in a plane transverse to the axis of rotation of the head, and a wire 20 guiding unit at each side of the flexing unit having rollers therein arranged similarly to the rollers in said cylindrical member and defining a wire receiving pass, the longitudinal axis of the wire receiving pass in the guide units coinciding with the axis of rotation of said head.
- 25 8. In a wire straightening machine, a stationary frame structure, a flexing head rotatably supported on said structure, said head having a longitudinal opening therethrough, a transversely adjustable frame in said head having a longitudinally extending opening therethrough, a cylindrical member in the opening in said frame, a bearing being provided between the outside of the cylindrical member and the interior of said frame, means for adjusting said frame transversely of the head, a plurality of rollers carried in said cylindrical member, the peripheries of which cooperate to define a wire receiving pass, the axes of the rollers being in a plane transverse to the axis of rotation of the head, a wire guiding unit at each side of the flexing unit having rollers therein arranged similarly to the rollers in said cylindrical member and defining a wire receiving pass, the longitudinal axis of the wire receiving pass in the guide units coinciding with the axis of rotation of said head.
- 30 9. In a wire straightening machine, a stationary frame structure, a flexing head rotatably supported in said frame structure, said head having hollow trunnions on the side faces thereof projecting into the frame structure, bearings in the frame structure engaging said trunnions, an eccentrically positioned flexing unit supported in said head and about which the head may revolve, cooperating means on the frame and flexing member for holding the latter against rotation with the head, and a wire guide at each side of the frame structure beyond the ends of said trunnions for supporting the wire in a position which is axial to the center of rotation of the head, said wire guides providing the only support for the wire as it passes from the guides through the flexing unit, the hollow trunnions

being of sufficient internal diameter to provide for the angular displacement of the wire, said guides being adjustable toward and away from the ends of the trunnions.

10. In a wire straightening machine, a flexing unit comprising a rotatably supported outer member, an inner member eccentrically positioned within the outer one and having a wire receiving pass therethrough of a shape and diameter conforming to the size of the wire being straightened, said outer member being rotatable about the inner one, a supporting structure in which the outer member is mounted, means arranged for relative oscillating movement connecting the inner member and the supporting structure for holding the inner member against rotation, guiding units at each side of the flexing unit having relatively fixed wire receiving passes therethrough whereby the wire is flexed without rotating the wire, and driving means on the periphery of said outer member.

11. A wire straightening device comprising a rotary head supported on hollow trunnions for rotation, a frame having bearings for the trunnions of said rotary head on which said rotary head is supported, a normally stationary guiding unit at each end of the rotary head, a flexing member having a pass therethrough eccentrically positioned in the rotary head and about which the head revolves, the head thereby serving to transmit a gyratory transverse movement to the flexing member, the pass in the flexing member being out of alignment with the guiding units, and means connecting the flexing member and frame and having an oscillating and a reciprocating connection with one of them for holding the flexing member against rotation while allowing for the gyratory transverse movement thereof.

12. In a wire straightening machine, spaced apart wire guiding means through which the wire is pulled, a flexing unit between the spaced apart wire guiding means comprising a member having a pass therethrough conforming substantially to the diameter and shape of the wire, which pass is positioned eccentrically to the axis of the wire as it passes through the guides, means for moving said member through a circular path about the axis of the wire, a supporting frame, and means on the supporting frame for holding said member against free rotation while permitting movement thereof in a circular path, said last named means being independent of said means for moving the member through a circular path.

13. In a wire straightening machine, a wire flexing unit comprising an inner member having a wire receiving pass therethrough, an outer member rotatable about the inner one and in which the inner one is eccentrically positioned, a fixed support for the outer member at each end thereof, rotation of the outer member imparting a wobbling motion to the inner one, and means on the fixed support engaging the inner member for holding it against rotation with the outer member.

14. In a wire straightening machine, a rotatable head having hollow trunnions thereon and having a driving surface on its periphery, a frame in which the trunnions are rotatably carried, an eccentrically adjustable frame carried in the head, said second frame having an opening therethrough providing an internal bearing surface, a cylindrical member in said opening about which the second frame may revolve with the head, said member having a wire receiving pass therethrough, said pass normally being eccentric

to the axis of rotation of said head, due to the eccentricity of the frame, and means beyond the ends of the trunnions constituting the only wire guiding and supporting elements for holding the wire at each side of the cylindrical member.

15. In a wire straightening machine, a rotatable head having hollow trunnions thereon, a frame in which the trunnions are rotatably carried, an eccentrically adjustable frame carried in the head, said second frame having an opening therethrough providing an internal bearing surface, a cylindrical member in said opening about which the second frame may revolve with the head, said member having a wire receiving pass therethrough, said pass normally being eccentric to the axis of rotation of said head, due to the eccentricity of the frame, means for adjustably changing the eccentricity of said second frame, and adjustable wire guides beyond the ends of 20 the trunnions constituting the support for the wire at each side of the cylindrical member, the internal diameter of the trunnions being sufficient to provide for the angular displacement of the wire between the cylindrical member and said 25 guides.

16. In a wire straightening machine, spaced apart wire guiding means through which the wire is pulled, a flexing unit between the spaced apart wire guiding means comprising a member 30 having a wire receiving pass therethrough, which pass is positioned eccentrically to the axis of the wire so it passes through the guides, means for moving said member through a circular path about the axis of the wire, a supporting frame, 35 and means on the supporting frame for holding said member against free rotation, while permitting movement thereof in a circular path, said last named means being independent of said means for moving the member through a circular path.

17. Apparatus for straightening rod-like metal stock, which includes stock-flexing devices extending around the stock in rolling contact therewith and confining the stock from independent 45 lateral movement, an arbor formed with a passage for the longitudinally moving stock, and formed hollow intermediate its ends and therein supporting said stock-flexing devices, supporting means in which the ends of said arbor are supported holding the arbor in a position offset from the center of the longitudinal stock-path, said supporting means being rotatable about said path-center and causing revolution of the arbor and stock-flexing devices about said path-center; 50 the ends of said arbor having anti-friction journals with said supporting means preventing rotation of the arbor thereby.

18. In a straightening machine, apparatus for finish-straightening long rod-like stock moving 55 longitudinally, which includes two circular arrangements of rollers, as fulcrum roller sets, respectively located around the path of longitudinal movement of the long stock, and spaced from one another by a comparatively short distance, the 60 center of said circular arrangements being in alignment with the center of the longitudinal stock-path, a third circular arrangement of rollers as a stock-flexing system, located intermediate said fulcrum roller-sets but supported 65 in position establishing the center of the flexing-roller system slightly eccentric to the centers of the circular fulcrum-roller sets; all said individual rollers having trunnions supported transversely of the stock-path and adapted for rolling engagement with the longitudinally moving

long stock; stationary supporting means for the fulcrum-roller sets; supporting means for the rod-flexing roller-system; and means imparting an exclusively revolutionary movement in small circles to the portion of said supporting means which carries said flexing-roller system, whereby the relatively short portions of the moving long stock progressively moving between the two fulcrum-roller sets is flexed in small circles about the center of its path of longitudinal movement. 5

19. In a straightening machine, apparatus for finish-straightening long rod-like stock moving longitudinally, which includes two circularly arranged sets of rollers, as fulcrum-rollers; stationary supporting means in which said sets respectively are located around the path of longitudinal movement of the long stock, and spaced from one another by a comparatively short distance, and with the centers of the sets in line with the center of longitudinal movement of the long stock; 10 a system of stock-flexing rollers, supporting means for said roller-system in which the rollers are mounted in a circle intermediate said fulcrum-roller sets; and means revolving the portion of said supporting means in which said 15 flexing system is mounted, in small circles, about the center of longitudinal movement of the long stock while the supporting means is held from rotation whereby the flexing roller system itself is given a movement exclusively of revolution and 20 the short portion of the long stock between the two sets of fulcrum-rollers is flexed in small circles about its center of longitudinal movement. 25

20. In a straightening machine, apparatus for finish-straightening long rod-like stock fed thereto, continuously in one direction, which includes two sets of fulcrum rollers arranged comparatively close together along the path of longitudinal stock-movement, the rollers of each set 30 extending around said path and having trunnions arranged transversely of said path; stationary supporting means for said fulcrum roller sets whereby they hold the moving stock in its path while the individual rollers are rotated by 35 the moving stock; a system of stock-flexing rollers arranged in a circle between said sets of fulcrum-rollers; supporting means for said flexing-roller system and in which trunnions of the rollers are mounted transversely of the path of 40 the stock; mechanism revolving the portion of said supporting means in which said flexing-rollers are mounted, in relatively very small circles about the center of the path of longitudinal 45 stock-movement while said supporting means is held from rotation and while the individual flexing rollers are being rotated by the stock moving between them, thereby revolving the stock in passage from one of the two sets of fulcrum-rolls to the other, in very small circles about the 50 center of its path of longitudinal movement. 55

21. In a straightening machine, apparatus for straightening long rod-like stock moving longitudinally, which includes two circular arrangements of rollers, as fulcrum roller sets, respectively located around the path of longitudinal movement of the long stock and spaced from one another by a comparatively short distance, the centers of said circular arrangements being in alignment with the center of the longitudinal 60 stock path, a third circular arrangement of rollers as a stock-flexing system, located intermediate said fulcrum roller sets but supported in positions 65 establishing the center of the flexing roller system slightly eccentric to the centers of the circu- 70

lar fulcrum roller sets, all said individual rollers being supported for rotation on axes transverse to the stock path and adapted for rolling engagement with the longitudinally moving long stock; stationary supporting means for the fulcrum roller sets; supporting means for the rod-flexing roller system; and means imparting an exclusively revolutionary movement in small circles to the portion of said supporting means which carries said flexing roller system, whereby the relatively short portions of the moving long stock progressively moving between the two fulcrum roller sets is flexed in small circles about the center of its path of longitudinal movement.

22. In a straightening machine, apparatus for straightening long rod-like stock fed thereto continuously in one direction, which includes two sets of fulcrum rollers arranged comparatively close together along a path of longitudinal stock movement, the rollers of each set extending around said path and being supported for rotation on axes transverse to said path, stationary supporting means for said fulcrum roller sets whereby they hold the moving stock in its path while the individual rollers are rotated by the moving stock, a system of stock flexing rollers arranged in a circle between the sets of fulcrum rollers, supporting means for said flexing roller system wherein the rollers are mounted for rotation on axes transverse to the path of the stock; mechanism revolving the portion of said support-

ing means in which said flexing rollers are mounted in relatively very small circles about the center of the path of longitudinal stock movement while said supporting means is held from rotation and while the individual flexing rollers are being rotated by the stock moving between them, thereby revolving the stock in passage from one of the two sets of fulcrum rollers to the other in very small circles about the center of its path of longitudinal movement.

23. A wire straightening device comprising a rotary head supported on hollow trunnions for rotation, a frame having bearings for the trunnions of said rotary head on which said rotary head is supported, a normally stationary guiding unit at each end of the rotary head, a flexing member having a pass therethrough eccentrically positioned in the rotary head and about which the head revolves, the head thereby serving to transmit a gyratory transverse movement to the flexing member, the pass in the flexing member being out of alinement with the guiding units, a stationary guide member on the frame, and a holding means engaging the flexing member and the guide and movable up and down with respect to the guide and back and forth with respect thereto for anchoring the flexing member against rotation while permitting it to be carried around eccentrically.

JACOB T. LEECH.
